Application March 10, 1933, Serial No. 660,275

25 Claims. (Cl. 62—120.5)

This invention relates, generally, to refrigeration apparatus of the intermittent absorption class, and more particularly to improvements in means for returning residue liquid from the evaporator section of the apparatus to the generator absorber section at the beginning of a cycle of operation, which beginning is characterized by what is known as the heating-condensing period.

Means for performing this transfer of residue liquid is described and claimed in Letters Patent No. 1,816,975, dated August 4, 1931, the present invention being directed particularly to improvements in the type of liquid return disclosed in said patent.

Briefly, the apparatus in connection with which the liquid return is employed comprises a closed system involving a generator-absorber section, an evaporator section, and communicative means for conveying refrigerant fluid between the sections in the attainment of a complete operative cycle, together with condensing means and means for intermittently supplying heat to the generator-absorber section, it being understood that the system contains a refrigerant liquid and a suitable absorbent liquid in proper proportions and, preferably, in sufficient quantity to practically fill the generator-absorber when all of the mixture is present therein.

When heat is applied to the generator-absorber, the mixture contained therein boils and the vapors, after being dehydrated as completely as possible, are condensed and the resultant liquid is delivered to the evaporator section of the apparatus. Upon the cessation of heat, the practically pure anhydrous refrigerant in the evaporator gradually gasifies and returns to the generator-absorber section where it is reabsorbed. Any liquid left in the evaporator section at the conclusion of the evaporating period, and which consists principally of absorbent condensate resulting from vapors that got past the dehydrator during the heating-condensing period, is known as the residue liquid.

At this point it may be explained that, as shown in the aforesaid Letters Patent, the evaporator section of the apparatus is above the plane of the generator-absorber section and the liquid return tube or conduit extends from a sump or low point in the evaporator section upwardly and thence laterally and downwardly into the generator-absorber section, the same being in the nature of a siphon. It is through this tube or conduit that the residue liquid is transferred from the evaporator section to the generator-absorber section, and the principle upon which it operates

may be explained as follows: At the beginning of the heating-condensing period the pressure throughout the system rises rapidly and, as a consequence thereof, the liquid in the generator-absorber section, and the residue liquid in the evaporator section, are forced up the respective branches of the liquid return tube or conduit, trapping between the two rising columns of liquid the gas that occupied the tube or conduit under the original internal low pressure condition of the apparatus, and which gas is particularly rich in refrigerant, and, by reason of the same being wholly or partially absorbed by the rising liquid, the two columns thereof are caused to approach each other and effect a sufficiently continuous body of liquid throughout the length of the liquid return tube or conduit to cause a siphonic action to be set up which draws over into the generator-absorber section of the apparatus, practically all of the residue liquid that was present in the evaporator section.

In the apparatus disclosed in the aforesaid patent, a part of the liquid return tube or conduit is in intimate heat exchanging relation to the hot vapors as they rise through the vapor delivery conduit during the heating-condensing period, and this is for the purpose of elevating the temperature of such part of the liquid return tube so as to cause any refrigerant liquid which might tend to pass therethrough during the condensing period to flash into gas and interrupt the siphonic action so as to avoid robbing the evaporator of any of its charge of anhydrous refrigerant. In some cases this arrangement was found to be too effective and actually prevented the return of all of the residue liquid. It was observed that, at times, the siphonic action would be stopped by the flashing into gas of a relatively small amount of refrigerant liquid that would return, early in the operation, with some of the absorbent liquid and, as a consequence, an appreciable amount of residue liquid would be left in the evaporator. In other words, sufficient time would not elapse between the start of the heating-condensing period and the heating up of the liquid return tube or conduit to allow a complete return of the accumulated residue liquid.

It is the fundamental purpose of the present invention to provide means that will insure a sufficient time lag between the beginning of the heating-condensing period, when the liquid return tube is relatively cool, and the stage in the progress of such period when said tube is heated, to insure a substantially complete return of the residue liquid; and which means thereafter will

maintain the temperature of the liquid return tube high enough to obviate any possibility of the return of pure anhydrous refrigerant during the remainder of the heating-condensing period.

Again, and more broadly, the invention may be said to have as its main purpose the provision of means for effecting the return of residue liquid from the evaporator section of the apparatus to the generator-absorber section thereof for a relatively definite time during the early stage of a cycle of operation and which will function thereafter to positively prevent the return of anhydrous refrigerant.

As to the present preferred form of the invention, its object may be recited as that of providing heat conducting means, desirably in the nature of a so-called "heat-bar", between the liquid return tube and some part of the system whose temperature is materially elevated during the heating-condensing period, and wherein the mass of this heat conducting means or bar is utilized to effect a sufficient delay in the transmission of heat to the liquid return tube to allow ample time for the return of the residue liquid before the tube becomes hot. Furthermore, when the mass of the aforesaid heat conducting means or bar once becomes hot, it is not readily cooled by any small slugs of anhydrous refrigerant that might, for any reason, pass through the liquid return tube. Consequently, after said heat conducting means or bar once reaches a high temperature, it is extremely effective in preventing the return of anhydrous refrigerant and thus guards against robbing the evaporator of its full charge of refrigerant for the subsequent cooling period.

The invention is susceptible to several modifications. For example, in place of the heat conducting means or heat bar above referred to, means may be associated with the liquid return tube for sustaining in contact therewith a body of cool liquid which is later displaced by a body of heated liquid, thereby to effect the same result as that above described of maintaining the liquid return tube cool for a certain period of time and thereafter causing it to be heated.

As a further modification, means may be provided for applying hot vapors to the outside of the liquid return tube to heat it up at the proper time.

A further means, which may be used alone or in combination with those above described, for attaining the purpose of the invention, is a vent for the siphon-like liquid return conduit, which vent may be in the nature of a tube that leads from a high part of said conduit to a point in the gas return conduit of the system below the minimum liquid level in the generator-absorber and so arranged that its lower end is closed by liquid from the generator-absorber during the heating-condensing period and is open when said liquid is displaced by the returning gas during the evaporating-absorbing period, the venting of the liquid return tube obviously preventing any siphonic action after the heating-condensing period has ceased.

The several embodiments of the invention above referred to are illustrated in the accompanying drawings wherein Fig. 1 is a diagrammatic representation of an intermittent absorption refrigerating machine or apparatus embodying the "heat bar" for effecting delayed transmission of heat from the vapor delivery conduit to the liquid return tube, this embodiment also including the vent for said tube; Fig. 2 is a sectional detail, on a somewhat larger scale than that of the pre-

ceding view, through the heat bar and the liquid return tube and vapor delivery conduit to which it is attached, the plane of section being indicated by the line 2-2 of Fig. 1; Fig. 3, which is on the same scale as Fig. 2, is a sectional detail of the junction between the liquid return tube or conduit and the vent tube; Fig. 4 is a view, similar to Fig. 1, showing the form of the invention in which means is provided for sustaining a body of hot liquid in contact with the high part of the liquid return tube or conduit during the latter part of the heating-condensing period; Fig. 5 is a fragmentary view of the refrigeration apparatus or machine showing a further modification which, in all other respects than those revealed, is identical with that illustrated in Fig. 4; and Fig. 6 is a diagrammatic representation of an intermittent absorption refrigerating machine or apparatus embodying a further modification of the invention.

The corresponding parts of the apparatus, aside from the elements of the present invention, will be designated by the same reference characters throughout the several views of the drawings.

The vessel which constitutes the generator-absorber is designated 1 and a vapor delivery conduit 2 leads therefrom to the bottom of a receiver vessel 3 which communicates, through a tubular column 4, with the evaporator 5. The vessel 1 will be referred to in some instances as the generator-absorber section of the apparatus, while the parts 3, 4 and 5 will be referred to as the evaporator section. A part 2a of the vapor delivery conduit constitutes a dehydrator, and a coiled portion 2b thereof forms the condensing unit, beyond which the conduit is shown as reduced in diameter and as terminating adjacent the bottom of the vessel 3. A gas return conduit 6 leads from the evaporator section of the apparatus or, more specifically, from the top of the vessel 3, to the generator-absorber section, the same entering the lower portion of the vessel 1 and terminating therein below the minimum liquid level indicated by the line a. The maximum liquid level in said vessel is shown by the line b.

Means for delivering heat to the generator-absorber section is indicated at 7, and may consist of a suitable hydrocarbon burner supported in operative relation to the vessel 1.

It will be readily understood by those familiar with the class of machines to which this invention pertains that the condensing unit or coil 2b, desirably together with the dehydrator 2a, is enclosed in a tank of cooling liquid, and that the evaporator 5 is placed inside the refrigeration compartment of a suitable cabinet, the receiver 3 preferably being insulated from such compartment. A showing of these features was omitted for the sake of clearness as their inclusion would have necessitated a less diagrammatic representation of the more important parts of the apparatus.

The liquid return tube or conduit is designated 8 and leads from a low point or sump in the evaporator section of the apparatus, as from the bottom of the column 4, upwardly through said column and through the vessel 3 and out the top thereof, continuing upwardly and laterally therefrom to a relatively high point where it turns and descends to the generator-absorber section, which is at a considerably lower elevation than the evaporator section, entering the vessel 1 and terminating therein at a point well below the maximum liquid level. In fact, it is shown in the present instance as having its end disposed below

the minimum liquid level. It will be observed that the end portions of the liquid return tube or conduit 8 are considerably smaller in diameter than the intermediate portion. The end portions 5 of the liquid return tube being of relatively small diameter, cause the liquid to rise therein at a reasonably rapid rate during the beginning of the heating period when the pressure is rising rapidly in the system, and as a consequence, the siphonic 10 action is initiated early in this phase of the cycle of operation; and by having the middle portion of the tube of greater diameter avoids subsequent carrying over of liquid by bubbles of gas entering the receiving end of the tube, as such bubbles 15 will break into the portion of the tube of larger diameter and allow the liquid to flow back into the evaporator.

In the form of the invention illustrated in Figs. 1 to 3, a so-called "heat bar" in the form of 20 a relatively massive body of metal, and designated 10, joins adjacent portions of the vapor delivery conduit 2 and the liquid return tube or conduit 8, the bar or mass of metal being in intimate heat exchanging relation to the conduits, as by being 25 welded thereto. This arrangement is best illustrated in Fig. 2.

At the conclusion of a cycle of operation the heat bar 10 is cool; the mixture of refrigerant and absorbent liquids stands in the generator-absorber 30 to about the level indicated by the dotted line b, and the residue liquid may stand in the evaporator end of the system to the level indicated by the dotted line c.

To start a cycle of operation, heat is applied 35 to the generator-absorber as by lighting the burner 1. As a result thereof, the mixture within the vessel 1 boils and the vapors ascend through the conduit 2 and are dehydrated, at least to a very high degree, while passing through the dehydrator 2a. The refrigerant vapors pass on through the condensing unit or coil 2 and are condensed therein and gravitate to the evaporator section—more accurately, to the receiver 3. In the meantime, the pressure within the system has 40 risen rapidly and has forced some of the residue liquid in the evaporator section and some of the mixture in the generator-absorber section upwardly into the respective ends of the liquid return tube or conduit, and the gas that is trapped within 45 said tube or conduit between the rising columns of liquid becomes more or less absorbed by the liquid drawing the two columns toward each other until a sufficiently continuous body of liquid is established within the return tube or conduit to 50 set up a siphonic action that will carry all, or practically all, of the residue liquid from the evaporator section over into the generator-absorber section.

During this time, the heat given off by the 55 vapors rising through the delivery conduit 2 has gradually elevated the temperature of the heat bar 10 until by the time the residue liquid is returned, said bar has transmitted the heat to the liquid return tube or conduit, so that in case any 60 of the anhydrous refrigerant tends to siphon over into the generator-absorber, it will, upon reaching the zone of heat given off by the bar 10 flash into gas and interrupt any siphonic flow that may have been started. Thus, during the remainder 65 of the heating period there is no liability of withdrawing the pure anhydrous refrigerant liquid from the evaporator section of the apparatus that is being delivered thereto from the condenser. In order to obtain the maximum in the transfer of 70 heat from the hot vapors in the conduit 2 to liquid 75

that flows down the conduit 8, said conduits are arranged with the latter above the former, where the heat bar connects the two, so that the floating vapors will be in more intimate heat exchanging relation to said bar, as will also the liquid 5 which flows down the lower side of the conduit 8.

As a further means of positively arresting siphonic action at the conclusion of the heating period, I may employ a vent for the liquid return conduit, the same being shown as a tube 11 10 whose upper end opens into the larger portion of the conduit 8 adjacent the high part of said conduit, as illustrated in detail in Fig. 3, said tube extending downwardly to where it joins the gas return conduit 6 below the plane of the minimum 15 liquid level in the generator-absorber section of the apparatus, the tube 11 being increased in diameter approximately to that of the conduit 6 downwardly from a point substantially midway between its ends. 20

At the conclusion of a cycle of operation, the liquid stands in the lower ends of the gas return conduit 6 and tube 11 to a level corresponding to the maximum liquid level in the generator-absorber section of the apparatus, indicated by 25 the dotted line b. During the heating-condensing period when the pressure within the system is high, the liquid is forced up into the lower portion of the conduit 6 and into the larger end of the tube 11. At the conclusion of such period, 30 however, and during the cooling-evaporating period which follows, the liquid that was in the lower portions of the gas return conduit 6 and tube 11 is displaced by the refrigerant gas as it 35 returns through said conduit to the generator-absorber for re-absorption by the relatively weak liquor therein, thereby unsealing the vent tube. Thus it will be seen that, from the very beginning of the cooling-evaporating period, the liquid return tube or conduit is vented which will positively 40 prevent its functioning as a siphon to rob the evaporator of its full charge of anhydrous refrigerant.

In the form of the invention illustrated in Fig. 4, a closed receptacle 15 encloses the high part 45 of the liquid return tube or conduit 8, and the same communicates through a tube 16 with a vessel 18 that surrounds a part of the vapor delivery conduit 2. It will be observed that the tube 16 opens into the vessel 18 adjacent the bottom 50 of the latter, and, as indicated, said vessel is practically filled with a liquid, which may be water.

At the beginning of a cycle of operation, the parts are relatively cool including, of course, the receptacle 15 and the portion of the liquid return tube or conduit with which it is associated. When the heating period is started and the hot vapors begin to ascend through the delivery conduit 2, heat is thus imparted to the liquid in the 60 vessel 18 and eventually sufficient vapor will be generated within said vessel to force the hot liquid up through the tube 16 and into the receptacle 15 where it will warm the adjacent portion of the liquid return tube or conduit 8 thereby to prevent 65 siphoning of anhydrous refrigerant liquid, by causing it to flash into gas. Sufficient time is afforded, however, before this heating up of the liquid return conduit takes place to permit the return of the residue liquid from the evaporator 70 section of the apparatus to the generator-absorber section thereof.

A slight modification of the form of the invention just described is illustrated in Fig. 5, where a revised part of the diagram of Fig. 4 is shown. 75

In other respects, the system may be as illustrated in the previous view. In Fig. 5 a vessel 18^a is substituted for the vessel 18 of Fig. 4, and it is placed inside the generator-absorber 1; and the tube 16^a, which is the equivalent of tube 16 of the former modification, extends down through the top portion of the generator-absorber 1 and joins the top of the vessel 18^a. The vessel 18^a contains a body of liquid, and as it is caused to boil by the surrounding heat in the vessel 1, its vapors will ascend through the tube 16^a and fill the receptacle 15, causing the heating up of the adjacent part of the liquid return tube or conduit 8. It will be understood, of course, that the boiling of the contents of the vessel 18^a is sufficiently delayed to permit normal functioning of the liquid return tube or conduit 8 so as to insure return of the residue liquid from the evaporator section of the apparatus to the generator-absorber section. It will be noted that the receptacle 15 and tube 16 or 16^a are arranged to drain toward the vessel 18 or 18^a so that all liquid or condensate will gravitate to the latter. Here it may also be explained that in Fig. 4, the tube 16 may terminate at the top of the vessel 18, in which case only the vapors of the liquid within said vessel would be communicated to the receptacle 15; and reversely, the tube 16^a in Fig. 5 may be continued to the bottom of the vessel 18^a so that in this case the heated liquid would be transferred by the action of the vapor in said vessel to the receptacle 15. These alternative forms are so obvious that specific illustration is deemed unnecessary.

In the modification illustrated in Fig. 6, condensate drains from the dehydrator 2^a through a tube 20 to a vessel 21 to a height at which it overflows through a tube 22 into a sleeve-like receptacle 23 that surrounds a portion of the liquid return conduit 8 adjacent the high part of the latter. The receptacle 23 drains, through a tube 24 into the generator-absorber section of the apparatus, said tube being shown as entering the vapor delivery conduit a short distance above the vessel 1. To prevent the siphoning of liquid from the vessel 21 through the overflow tube 22, said tube is vented through a pipe 25 to the tube 20.

Prior to the initiation of a cycle of operation, the parts of the apparatus are cool, as is also the liquid in the vessel 21. Upon the starting of a cycle of operation by applying heat to the generator-absorber, as by lighting the burner 7, the liquid in the vessel 1 starts to boil and the hot vapors rise through the relatively large vapor delivery conduit 2 and as they pass through the dehydrator 2^a, the absorbent vapors condense and the resultant warm liquid gravitates through the tube 20 to the vessel 21, causing said vessel to overflow through the tube 22 into the receptacle 23, and since said tube 22 communicates with the bottom of the vessel 21, the cool liquid will first be transmitted to the receptacle 23. The flow of relatively cool liquid continues long enough to insure a siphoning of the residue liquid from the evaporator section of the apparatus to the generator-absorber section, after which warm liquid overflows from the vessel 21 into the receptacle 23 and, heating the liquid return tube or conduit, prevents siphoning of anhydrous refrigerant liquid by causing it to flash into gas when it reaches the relatively warm zone adjacent the high portion of the tube or conduit 8. At the conclusion of each heating period, liquid remains in the vessel 21 to the height of the overflow tube 22, and this liquid cools during the

subsequent relatively prolonged cooling-evaporating period of the cycle of operation.

Having thus described my invention, what I claim is:

1. The combination with refrigeration apparatus of the intermittent absorption type wherein a refrigerant fluid and an absorbent fluid are used, and comprising a closed system involving a generator-absorber section, an evaporator section, and communicative means for conveying refrigerant fluid between the sections in the attainment of a complete operative refrigeration cycle, together with condensing means and means for intermittently supplying heat to the generator-absorber section, the portion of each cycle during which the heat supplying means is effective being known as the heating period, and a conduit for returning liquid from the evaporator section to the generator-absorber section at the beginning of a heating period; of means that becomes effective a predetermined and relatively prolonged interval of time after the beginning of the heating period for maintaining a part of said conduit hot during the remainder of said period, thereby to vaporize liquid refrigerant entering said part of the conduit and consequently interrupt the flow of liquid through the conduit so as to prevent the return of liquid thereafter.

2. The combination with refrigeration apparatus of the intermittent absorption type wherein a refrigerant fluid and an absorbent fluid are used, and comprising a closed system involving a generator-absorber section, an evaporator section, and communicative means for conveying refrigerant fluid between the sections in the attainment of a complete operative refrigeration cycle, together with condensing means and means for intermittently supplying heat to the generator-absorber section, the portion of each cycle during which the heat supplying means is effective being known as the heating period, and a conduit for returning liquid from the evaporator section to the generator-absorber section at the beginning of a heating period, of means for effecting a materially delayed transmission of heat to a part of said conduit from a portion of the system whose temperature is raised to a relatively high degree during the heating period thereby to vaporize liquid refrigerant entering said part of the conduit so as to interrupt the flow of liquid through the conduit and prevent the return of liquid thereafter.

3. The combination with refrigeration apparatus of the intermittent absorption type wherein a refrigerant fluid and an absorbent fluid are used, and comprising a closed system involving a generator-absorber section, an evaporator section, and communicative means for conveying refrigerant fluid between the sections in the attainment of a complete operative refrigeration cycle, together with condensing means and means for intermittently supplying heat to the generator-absorber section, the portion of each cycle during which the heat supplying means is effective being known as the heating period, and a conduit for returning liquid from the evaporator section to the generator-absorber section at the beginning of a heating period; of means rendered effective an appreciable interval of time after the beginning of the heating period by heat from a part of the system whose temperature is elevated to a relatively high degree during the heating period for imparting heat to a part of the aforesaid conduit thereby to vaporize liquid refrigerant entering said part so as to interrupt the

flow of liquid through the conduit and prevent the return of liquid thereafter.

4. The combination with refrigeration apparatus of the intermittent absorption type wherein a refrigerant fluid and an absorbent fluid are used, and comprising a closed system involving a generator-absorber section, an evaporator section, and communicative means for conveying refrigerant fluid between the sections in the attainment of a complete operative refrigeration cycle, together with condensing means and means for intermittently supplying heat to the generator-absorber section, the portion of each cycle during which the heat supplying means is effective being known as the heating period, and a conduit for returning liquid from the evaporator section to the generator-absorber section at the beginning of a heating period; of vent means leading from a part of said conduit and liquid sealed by liquid from the generator-absorber section of the system during the heating period and cleared of liquid by gas returning from the evaporator section of the system to the generator-absorber section during the evaporation-absorbing period thereby to vent said conduit and prevent the return of liquid during the latter period.

5. In refrigeration apparatus of the class set forth including evaporator and generator-absorber sections and incorporating a conduit for returning residue liquid from the evaporator section to the generator-absorber section at the beginning of a heating period, means for maintaining a part of said conduit at a relatively low temperature for a predetermined interval of time after the beginning of each heating period and for maintaining said part at a relatively high temperature during the remainder of the heating period.

6. In refrigeration apparatus of the class set forth including evaporator and generator-absorber sections and incorporating a conduit for returning residue liquid from the evaporator section to the generator-absorber section at the beginning of a heating period, means permitting a part of said conduit to remain at a relatively low temperature for a predetermined interval of time after the beginning of each heating period and for then heating said part to a relatively high temperature and maintaining it so during the remainder of the heating period.

7. In refrigeration apparatus of the class set forth including evaporator and generator-absorber sections and a conduit for returning residue liquid from the evaporator section to the generator-absorber section at the beginning of a heating period, a heat absorbing body having considerable mass arranged in thermal contact with a part of said conduit, said body remaining at a relatively low temperature for a predetermined time during the early part of each heating period and then being heated and maintained at a relatively high temperature during the balance of the heating period.

8. In refrigeration apparatus of the class set forth including evaporator and generator-absorber sections and a conduit for returning residue liquid from the evaporator section to the generator-absorber section at the beginning of a heating period, a heat absorbing body having considerable mass arranged in thermal contact with a part of said conduit, said body being also in thermal contact with a part of the apparatus whose temperature is elevated to a relatively high degree during the heating period, the body

remaining at a relatively low temperature for a predetermined prolonged interval of time during the early part of each heating period and thereafter being heated and maintained at a relatively high temperature during the remainder of the heating period by reason of its thermal contact with the previously mentioned part of the apparatus.

9. In refrigeration apparatus of the class set forth including evaporator and generator-absorber sections and a conduit for returning residue liquid from the evaporator section to the generator-absorber section at the beginning of a heating period, means associated with said conduit for maintaining it relatively cool for a predetermined interval of time at the beginning of each heating period and for thereafter maintaining it at a relatively high temperature during the remainder of said period.

10. In refrigeration apparatus of the class described, in combination with a vapor delivery conduit and a valveless liquid return siphon, a heat conducting body of relatively large mass in thermal contact with the conduit and siphon.

11. In refrigeration apparatus of the class described, in combination with a vapor delivery conduit and a valveless liquid return siphon, a heat conducting element of relatively large mass connecting the conduit and siphon.

12. In refrigeration apparatus of the class described, in combination with a vapor delivery conduit and a valveless liquid return siphon, the latter being arranged above the former, a heat conducting element of relatively large mass connecting the top side of the vapor delivery conduit with the underside of the liquid return siphon.

13. In refrigeration apparatus of the class described, in combination with a vapor delivery conduit and a valveless liquid return siphon, a relatively heavy heat bar connecting adjacent parts of the conduit and siphon.

14. In refrigeration apparatus of the class set forth, in combination with the vapor delivery conduit and the liquid return conduit, a receptacle in intimate heat exchanging relation to a part of the liquid return conduit, a vessel at a lower elevation than said receptacle in similar relation to the vapor delivery conduit and containing a fluid, and means communicatively connecting said receptacle and vessel.

15. In refrigeration apparatus of the class set forth, in combination with the vapor delivery conduit and the liquid return conduit, a receptacle in intimate heat exchanging relation to a part of the liquid return conduit, a vessel surrounding the vapor delivery conduit and containing a body of liquid, and a tube communicatively connecting the receptacle and vessel and being so arranged as to permit the former to drain therethrough to the latter, said tube opening into the vessel adjacent the bottom thereof.

16. In refrigeration apparatus of the class set forth including evaporator and generator-absorber sections and a liquid return conduit through which residue liquid is returned from the evaporator section to the generator-absorber section of the apparatus, a receptacle in intimate heat exchanging relation to a part of said conduit and arranged to drain into the generator-absorber section, a vessel communicating with a part of the apparatus and so arranged as to receive hot condensate during the heating-condensing period of a cycle of operation, and communicative connections through which said vessel overflows into the aforesaid receptacle.

17. In refrigeration apparatus of the class set forth including evaporator and generator-absorber sections and a liquid return conduit through which residue liquid is returned from the evaporator section to the generator-absorber section of the apparatus, a receptacle in intimate heat exchanging relation to a part of said conduit and arranged to drain into the generator-absorber section, a vessel communicating with a part of the apparatus and so arranged as to receive hot condensate during the heating condensing period of a cycle of operation, communicative connections through which said vessel overflows into the aforesaid receptacle, and vent means communicating at its ends with parts of the refrigeration system on opposite sides of said vessel and bypassing the same.
18. In refrigeration apparatus of the class set forth, in combination with a liquid return conduit and a gas return conduit, a vent leading from an elevated part of the liquid return conduit and communicating with the gas return conduit at a point below the plane of the minimum liquid level in the generator-absorber section of the apparatus.
19. In refrigeration apparatus of the class set forth, in combination with a liquid return conduit and a gas return conduit, the former conduit being enlarged in diameter intermediate its end portions, a tube through which an elevated part of the enlarged portion of the liquid return conduit communicates with a part of the gas return conduit below the plane of the minimum liquid level in the generator-absorber section of the apparatus, said tube being enlarged in diameter from its junction with the gas return conduit for a material distance hereabove.
20. In refrigeration apparatus of the class set forth, including evaporator and generator-absorber sections and a siphon-like conduit for returning residue liquid from the evaporator section to the generator-absorber section of the apparatus, a tube through which the elevated portion of said siphon-like conduit is vented to the generator-absorber section and so arranged as to be sealed by liquid therefrom excepting during the evaporating-absorbing period of a cycle of operation.
21. In refrigeration apparatus of the class set forth, including evaporator and generator-absorber sections and a siphon-like conduit for returning residue liquid from the evaporator section to the generator-absorber section of the apparatus, a tube through which the elevated portion of said conduit is vented, said tube communicating at its lower end with the generator-absorber section through the gas return conduit of the apparatus and so arranged as to be sealed by liquid from the generator-absorber section excepting when such liquid is displaced by the returning gas.
22. In refrigeration apparatus of the class set forth including evaporator and generator-absorber sections and a conduit in constant open communication with both of said sections for returning residue liquid from the evaporator section to the generator-absorber section at the beginning of a heating period, means operating with a substantially definite time lag for effecting by conduction a materially delayed transmission of heat to said conduit from a part of the apparatus whose temperature is relatively high during the heating period.
23. In refrigeration apparatus of the class set forth including evaporator and generator-absorber sections and a conduit in constant open communication with both of said sections for returning residue liquid from the evaporator section to the generator-absorber section at the beginning of a heating period, means operating with a substantially definite time lag and influenced by the elevated temperature of the part of the apparatus that becomes heated during said period for transmitting heat by conduction to the aforesaid conduit a predetermined and relatively prolonged interval of time after the beginning of said heating period.
24. In refrigeration apparatus of the class described including an evaporator section and a generator-absorber section, and a siphon in constant open communication with both of said sections for returning residue liquid from the evaporator section to the generator-absorber section at the beginning of a heating period; means operating with a definite time lag that is rendered effective a material interval of time after the beginning of the heating period, by the elevated temperature of a part of the system heated to a relatively high degree during the heating period and to which said means is subjected, for imparting heat by conduction to a part of the siphon that is above the plane of its higher end.
25. In refrigeration apparatus of the class set forth, including an evaporator section and a generator-absorber section, and a liquid return conduit through which residue liquid is returned from the evaporator section to the generator-absorber section; a receptacle in intimate heat exchanging relation to a part of said conduit, a vessel arranged to be heated by the heat of the vapors generated in the generator-absorber section, said vessel containing a fluid, and means through which said receptacle and vessel communicate.

LEE S. CHADWICK.
